(57) **CLAIM**

The ornamental design for a table, as shown and described.

DESCRIPTION

FIG. 1 is a perspective view of the table;

FIG. 2 is a front elevational view of the table, the rear elevational view of which is identical;

FIG. 3 is a right side elevational view of the table, the left side elevational view of which is identical;

FIG. 4 is a top plan view of the table; and,

FIG. 5 is a bottom plan view of the table.

The broken lines in the drawings show portions of the table that form no part of the claimed design.

1 Claim, 5 Drawing Sheets

FIG. 1

FIG. 2

FIG. 3

FIG. 4

FIG. 5
